UNITED STATES PATENT OFFICE.

JAMES C. KRIDLER, OF WAPAKONETA, OHIO.

IRONING-BOARD.

SPECIFICATION forming part of Letters Patent No. 683,608, dated October 1, 1901.

Application filed March 6, 1901. Serial No. 49,786. (No model.)

To all whom it may concern:

Be it known that I, JAMES C. KRIDLER, a citizen of the United States, residing at Wapakoneta, in the county of Auglaize and State 5 of Ohio, have invented certain new and useful Improvements in Ironing-Boards; and I do declare the following to be a full, clear, and exact description of the invention, such as will enable others skilled in the art to which 10 it appertains to make and use the same.

The invention relates to ironing-boards.

The object of the invention is to provide a device of this character which may be readily and securely attached to the edge of a table, bench, or the like, provision being made 15 whereby a large range of vertical adjustment may be had to said benches, shelves, tables, or the like of different heights.

With these and other objects in view the 20 invention consists of certain novel features of construction, combination, and arrangement of parts, which will be hereinafter more fully described, and particularly pointed out in the appended claim.

25 In the accompanying drawings, Figure 1 is a perspective view illustrating the application of my invention, and Fig. 2 is a longitudinal sectional view.

Referring to the drawings, the numeral 30 1 denotes an ironing-board constructed in any well-known form, having secured transversely on its underside, near its forward end, a strip *b*. I provide a plate 6 in front of the guide-strip having a recess to form a depression *c* for a purpose to be presently explained.

35 The numeral 2 indicates a yoke or hanger secured to the under face portion of a clamping-jaw 3, with the arms or branches thereof extending upwardly from the sides or edges 40 of the clamping-jaw, the ends of the arms being pivoted to opposite sides or edges of the ironing-board, whereby a rocking or vibrating movement may be imparted to the said clamping-jaw. To the rear and in the upper

45 face portion of the clamping-jaw I secure a plate 4, having a screw-threaded opening therein which registers with a communicating opening formed in the clamping-jaw. A screw-threaded bolt 5 with a rounded upper 50 end passes through the opening of the clamping-jaw and connects with the screw-threaded opening in the plate 4. The bolt is provided

on its lower end with any well-known means whereby to operate the same. In the present instance I show a wheel for the purpose. 55 Approximating the central under surface of the ironing-board I hinge an arm *a*, and to the arm I connect a leg *b* by means of a sleeve *d*, embracing the same, whereby the leg is vertically movable on the arm by means of 60 the leg having a vertical slot *S* therein, through which passes a bolt 9, secured to the outer face portion of the arm, a thumb-nut 10, connected to the screw-threads of the bolt when tightened up, serving to hold the arm and 65 leg in an adjustable position.

To fasten the jaw and its connected end of the ironing-board to any desired object, the same is accomplished by turning the bolt 5 upward. This action tilts the front portion 70 of the jaw upward toward the object sufficiently to clamp the same between it and its connected end of the board, the rounded upper end of the bolt serving to engage the recess *c* of the plate 6 on the under side of the 75 board to prevent lateral displacement of the said bolt, thereby serving to hold the clamping-jaw to its work. The strip *b* on the under side of the board acts as an abutment for the edge of the object clamped between the jaw 80 and its coacting portion of the board.

From the foregoing description, taken in connection with the accompanying drawings, the construction, mode of operation, and advantages of my invention will be readily understood without requiring a more extended explanation. 85

Various changes in the form, proportion, and details of construction may be made within the scope of the invention without departing from the spirit or sacrificing any of the advantages thereof. 90

Having thus described my invention, what I claim, and desire to secure by Letters Patent, is— 95

The herein-described ironing-board having on its under side portion a hinged arm, a leg with a sleeve embracing the arm, a vertical slot formed in the leg, a screw-threaded bolt secured to the arm, and passing through the 100 slot, an operating-nut mounted on the bolt for adjusting the leg, a clamping-jaw at the inner end of the board, a hanger secured to the jaw and having its arms pivoted to the

edges of the board to permit of the jaw to rock, a plate with a screw-threaded opening therein secured to the jaw, having communication with an opening formed in the jaw, a 5 plate with a recess therein secured to the under side of the board, and opposite the plate of the jaw, and an operating screw-bolt with a rounded upper end passing through the opening of the jaw and engaging the 10 screw-threaded opening of the plate, whereby the rounded upper end of the operating-bolt is adapted to engage the recess of the plate

on the under side of the board when the jaw is clamped to its object, to prevent lateral displacement of said bolt, thereby serving to 15 hold the clamping-jaw to its work, substantially as specified.

In testimony whereof I have hereunto set my hand in presence of two subscribing witnesses.

JAMES C. KRIDLER.
